UNITED STATES PATENT OFFICE.

BENJAMIN FRANKLIN, OF CHICAGO, ILLINOIS.

GAME APPARATUS.

1,146,060.

Specification of Letters Patent. Patented July 13, 1915.

Application filed September 22, 1913. Serial No. 790,989.

To all whom it may concern:

Be it known that I, BENJAMIN FRANKLIN, a citizen of the United States, and a resident of Chicago, in the county of Cook and State 5 of Illinois, have invented certain new and useful Improvements in Game Apparatus; and I do hereby declare that the following is a full, clear, and exact description thereof, reference being had to the accompanying drawings, and to the letters of reference 10 marked thereon, which form a part of this specification.

This invention relates to a game apparatus designed to afford interesting and instructive amusement and at the same time 15 develop the skill of the player.

The apparatus consists essentially of a board or support upon which a geographical course is pictured, such, for example, as the 20 Panama Canal, suitably spaced for the purposes of the game, and a plurality of objects or pieces with which to play. The course is laid out in a manner approximating the true 25 course of the Panama Canal, and in order to instruct as well as to increase the interest of the player, the space on each side of the course is pictured to illustrate the topography of the country through which the canal passes, namely, the Canal Zone.

30 In the drawings:—Figure 1 represents a plan view of the board or support with the course depicted thereon. Fig. 2 is a view, in side elevation, of pieces, preferably of a form to represent ships, and with which 35 pieces the game is played upon the canal course in accordance with the rules of the game.

Referring more particularly to the drawings, the numeral 5 indicates a board or 40 other supporting device, having pictured upon it a geographical map, illustrating the Panama Canal Zone, 6, and adjacent territory.

7 indicates (on a scale exaggerated as to 45 its width) the Panama Canal laid out as a course for the play by a series of substantially parallel lines with spaces α of equal length. That is to say, said spaces may represent miles, half miles or other equal subdivisions of the total length of the canal. In this instance, miles are indicated and 50 forty-six spaces are used, this being the approximate length of the Panama Canal, said spaces being numbered consecutively on both 55 sides of the course from 1-46, inclusive, one set of numerals starting with the numeral 1

at one terminal of, or entrance to the canal, and the other set of numerals starting from the other terminal. Near one end b of the canal 7, one of the spaces, that marked c , 60 is selected and suitably marked to represent the Gatun locks, and at an equal distance from the other end b of the canal 7 is a similar space d , similarly marked to represent the Miraflores locks. Intermediate the 65 spaces c , d are certain of the spaces, e and f , for example, selected to represent the only places in the canal where the ships moving in opposite directions may pass each other with safety. 70

In connection with the board or support 5, I provide suitable playing devices. In the instance shown, there are two sets, g and h , of such devices, each representing a ship, and there are three devices in each set, although two or more devices may be comprised in each set. The two sets of devices g , h should be of distinguishing shape or ornamentation, and said pieces or ships are also provided with indicating means representing a fixed rate of speed for each piece or ship. I find it convenient to provide said space indicating means in the form of pegs representing funnels, the same being adaptable for grasping when moving the pieces. 80 For example, in Fig. 2 is illustrated a set of three ships, one ship having one funnel, another having two funnels and the other having three funnels. The said funnels indicate that the device or ship can travel on 90 the canal course in one move only, the number of spaces corresponding to the number of funnels on the moving ship. For example, a ship having one funnel can travel only at the rate of one mile in a given period of 95 time and this travel in the game will be represented by moving that ship only one space, while the ship having two funnels and thus capable of traveling two miles in the same time will be moved two spaces 100 only, and similarly the three funnel ship may be moved three spaces in each "move" or "play."

The game is played in the following manner: The contestants being at opposite ends 105 of the canal, each having all of his pieces or ships ready to enter the canal at that entrance, the object of the game is for one of the players to move his three ships through the canal before his opponent can move his 110 through in the opposite direction. The players move in turn one ship at a time or play,

and each player must get his first played ship through the locks nearest his entrance end of the canal before starting another ship into the canal. Each ship is moved only the space or spaces corresponding to its spaced or indicated rate of travel, but each ship must enter each of the locks when reached. For example, if a player starts from the Bay of Panama with a three mile ship, or a ship moving three spaces *a* at each play, his first play will land the ship into the space numbered 3 and his second play will land the ship in the space numbered 6. The third play will not be to the space 9 but only to the space *d*, representing the Miraflores locks, as each ship must enter and pass through both locks. In the subsequent plays, however, this ship may be moved its regular three spaces at a time until it reaches the Gatun locks, into which it must go, and then pass on at its regular speed. Similar stops must be made with similar other ships, but no two ships can occupy a lock at the same time. The ships of each set move toward each other, that is to say, in opposite directions. Should they meet on either of the "safe to pass" spaces *e* or *f*, they may so remain without penalty. However, if a player has a ship moving with sufficient speed that he can move it up from the space it last occupied to the space occupied by one of the ships of his opponent, the latter will have to retire his ship from the canal course to the starting point and begin all over again with that ship. The retiring of an opponent's ship is discretionary with the player making the retiring move, for he may have other objects in view, as for instance, to retire the said ship with one of his other ships. A ship which has been retired to the starting point must reenter the canal and proceed as before, and should it reach a space *a* occupied by one of the opponent's ships, the latter may be similarly retired. Two ships of the same set may occupy the same space (except a lock) at one time, and in this event they constitute a "blockade," thus preventing the opponent's ship from moving beyond the space so occupied. This blockade may be held indefinitely excepting in the event of the opponent seeking to pass the blockade with one of his ships and is without a possible move with either of his other ships. In such case, the blockade must be broken. When one contestant is holding blockade by two ships of his set, his third ship must be kept moving. Should a player succeed in passing two of his ships through the canal, and his one remaining ship be retired to the starting point by his opponent, he can, if he so desires, substitute one of his ships already through the canal for the one retired before it reenters the canal. Such privilege can occur only once during the

game. The game proceeds, the contestants playing alternately, until one set of ships is entirely through the canal and then the game may be called. The game may be played in tournament form for points in this manner. For instance, should one player safely move his entire set of ships through the canal, and the other player have one ship on the canal and needs to move that ship only five more spaces to have finished his entire trip through the canal, the player who has won the game would be entitled to one point for each space that his opponent has yet to go. Should his opponent have two ships upon the board, one having five spaces to go and one having nine spaces to go, the player would then be credited with fourteen points. In this manner several players may play in tournament with an objective number of points in view.

Any number of ships may be used and there may be two or more contestants on each side, but in no event can more than one ship be moved at a time, or that moved to a greater number of spaces in one play than the indicated speed of the ship.

During the progress of the game, the following rules must be observed:

Each ship must enter both locks and only one ship may occupy a lock at one time.

Each ship of each set must enter and pass through the lock nearest the ship's starting point before another ship of the same set may enter the canal.

Should a ship moving in one direction during the course of the play be caused to move upon a space occupied by the opponent's ship, the opponent's ship is retired to starting at the discretion of the player making the move. This rule applies to all spaces excepting the lock spaces and the spaces "safe to pass."

A ship having been sent back to the starting point is allowed to reenter the canal, and should its first move cause it to alight on a space occupied by one of the opponent's ships, the opponent's ship is retired to his starting point.

Two ships of one set may occupy any space other than a lock space at one time, thus forming a blockade. A blockade must be broken, however, when the opponent is unable to move any of his ships.

Should a player pass two of his ships through the canal, and his remaining ship is sent back to reenter the canal, he may substitute one of his ships already through for the one sent back, but this privilege may be exercised only once by that contestant during the game.

I am aware of the game called "pachisi" in which a spaced course is provided over which a number of pieces of men of a similar value, are moved, the movement of each piece being governed by chance, such as the

throwing of dice. Such a game is quite different from my game where each piece along the course is governed by a predetermined value and is adapted to be moved 5 along a course having two starting points, one starting point being the objective point for the other contestant, and vice versa, and where the movement of each piece along the course is governed by a predetermined value 10 of its own, thus bringing into the play the exercise of strategy not found in games where the movement of each piece is governed by chance.

The board or support upon which the 15 course is depicted may be of any shape or any convenient material, but I prefer a "folding" cardboard, such as commonly used for games. The pieces may be of any desired material or form, but I prefer the 20 contour of a ship, and while the rate of travel may be indicated by numeral or otherwise, I prefer to use one or more funnels, as above stated.

The geographical course may be depicted 25 by printing or otherwise directly upon the board or support of paper, linen or other fabric, and the latter affixed to one side of the board or support. Desirably, the course is depicted in appropriate colors.

30 Having described my improved game apparatus and the manner of its use in playing the game, I claim as my invention:

1. A game comprising a board or support, 35 upon one surface of which is depicted a course having a plurality of starting points and a plurality of objective points, said course being divided into a plurality of equal spaces, a plurality of pieces adapted

for movement on said spaces, each of said pieces being provided with means indicating the number of spaces said piece may travel at one time or move in the play. 40

2. A game apparatus comprising a board or support upon which is depicted a course having a plurality of starting points and a 45 plurality of objective points, said course being divided into a plurality of spaces of equal width, sets of pieces adapted for movement on said spaces toward each other, each piece of each set being provided with 50 means indicating the number of spaces each piece is allowed to move at one time, the starting point of one set of pieces being the objective point of the other set of pieces.

3. A game apparatus comprising a board 55 or support, upon which is depicted a course having a starting and a finishing point at each end thereof, spaces of equal width along the said course which are numbered consecutively from each starting point, sets 60 of pieces adapted for movement on the said numbered spaces toward each starting point of the course, certain spaces of the course being penalty spaces where each piece must stop and pass before another piece is started 65 on the beginning of the course and other spaces intermediate said stop spaces, upon which said pieces may rest without penalty.

In testimony, that I, claim the foregoing 70 as my invention I affix my signature in the presence of two witnesses, this 17th day of September A. D. 1913.
